D. M. WESTON,
SELF BALANCING CENTRIFUGAL MACHINE.
No. 82,049. Patented Sept. 8, 1868.

FIG. I.

FIG. II.

INVENTOR:

D. M. Weston.

UNITED STATES PATENT OFFICE.

DAVID M. WESTON, OF BOSTON, MASSACHUSETTS.

IMPROVED SELF-BALANCING CENTRIFUGAL MACHINE.

Specification forming part of Letters Patent No. 82,049, dated September 8, 1868.

To all whom it may concern:

Be it known that I, DAVID M. WESTON, of Boston, in the State of Massachusetts, have invented a new and useful Improvement in Self-Balancing Centrifugal Machines; and I do hereby declare that the following is a full, clear, and exact description of the construction and operation of the same, which will enable those skilled in the art to make and use the same, reference being had to the accompanying drawings, making part of this specification, and to the letters of reference marked thereon.

Figure 1 is a longitudinal sectional view of my invention, with the frame-work or floor on which it rests. Fig. 2 is a plan of the under surface of the floor or platform, showing also sections of the pulley to which the power is applied, and the bushing-spring and box at the bearing of the perpendicular shaft.

a is the revolving cylinder or receptacle, which contains the material to be operated upon. *b* is the perpendicular shaft, to which the cylinder *a* is firmly attached. *c* is the pulley, to which the driving-power is applied. *d* is the box, in which the shaft *b* revolves. *e* is a flexible easily-yielding spring, made of rubber or other elastic material, placed around the outer circumference of the box *d*, and within a stationary or fixed bushing, *t*, which is secured firmly to the cross-timbers *g* below, and attached firmly to the lower surface of the floor-timbers *h h h h*, on which the floor *i* rests.

The subject-matter of this invention consists in avoiding the injurious effects caused by the irregular or unequal distribution of material to be acted upon within the revolving cylinders of centrifugal machines described in the schedule annexed to the reissue of my former patent, dated January 14, A. D. 1868, No. 2,845; but by the use of a different method, to wit, in so mounting the machine as to cause it to revolve upon a flexible pivot-bearing at the base of the perpendicular shaft, instead of suspending it upon a flexible bearing or connection at the top of an upright shaft, thus reversing the former method.

Centrifugal machines have been made to revolve upon an upright shaft, with a pivot-bearing at the bottom; but a difficulty to be

overcome has been found, from their tendency to stagger or surge in starting with a charge of sugar or other semi-liquid material, which results in a heavy lurch, so great as to stop the revolution of the machine. Partially-flexible upper bearings have been applied to the shaft, near and below the cylinder, with a pulley attached between this and the lower bearing, as in the Fesher machine imported from Berlin. These machines cannot be charged before starting, and it has been found necessary to charge the cylinder with the material to be acted upon at speed.

An improvement on this machine has been patented in the United States, enabling the operator to charge the machine while stationary, which improvement consists in the application of an adjustable fixed bearing, applied above the cylinder, which is removed after starting and attaining a certain degree of speed. This requires the attention of a skillful operator to detach this adjustable bearing at the top at the proper moment.

In all centrifugal machines revolving upon fixed bearings great weight and strength of machinery are required to obtain a proper degree of stability, and revolving, as they do, at high speed, a very objectionable jar and concussion are produced. The same difficulty arises in a proportionate degree by the attempt to control the machine by the upper flexible bearings below the cylinder above described.

In my invention I dispense with the fixed bearings at the top and the partially-flexible upper spring-bearing below the cylinder. Power being applied by means of a driving belt attached to the pulley *c* below the platform or floor, the machine commences to revolve without any support or control to keep it in position other than the spring *e*, which is made so flexible as to have just sufficient strength to preserve the vertical position of the machine while stationary, but not so rigid as to exercise control over its revolutions in motion.

The tendency of the machine to oscillate from the center or stagger when starting is overcome without difficulty by making the upright shaft of a length not less than one and one-fourth time the diameter of the cylinder,

and the use of the spring *e* at the base, of the flexible character above described.

It is essential that the length of the upright shaft should be such as to permit the natural oscillation of the machine in starting within an angle sufficiently obtuse to keep the cylinder very nearly on a horizontal plane and the shaft nearly perpendicular. The natural tendency of the machine under these conditions is to find an axis of revolution in perfect *equilibrio*.

The pulley *c*, which surrounds the spring *e*, in order to prevent the driving-power of the belt from disturbing the perpendicular position of the machine, and also the spring, are parts of my former invention, before referred to, and no claim is made for these devices in this application.

What I now claim, and desire to secure by Letters Patent, is—

1. The application of the easy-yielding spring *e*, as the sole support of a centrifugal machine revolving upon an upright shaft resting upon a pivot-bearing at the base, and in combination with the shaft and pivot-bearing, substantially as above described.

2. The flexible spring *e*, in combination with the upright shaft *b*, made of sufficient length to prevent the natural oscillation of the machine at an obtuse angle, substantially as described.

3. The pulley *c*, affixed to the shaft *b* below the floor or platform *i*, so that the driving-power of the machine is wholly applied below the floor.

D. M. WESTON.
